UNITED STATES PATENT OFFICE.

JOHN MARTIN FIEDLER, OF WENTZVILLE, MISSOURI.

HORSE-DETACHER.

SPECIFICATION forming part of Letters Patent No. 372,902, dated November 8, 1887.

Application filed August 26, 1887. Serial No. 247,939. (No model.)

To all whom it may concern:

Be it known that I, JOHN MARTIN FIEDLER, of Wentzville, in the county of St. Charles and State of Missouri, have invented a new and Improved Horse-Detacher, of which the following is a specification, reference being had to the annexed drawings, forming a part thereof, in which—

Figure 1 is a perspective view of a vehicle to which my improved horse-detacher has been applied. Fig. 2 is a detail view of one of the ends of the singletree, showing the traces and singletree in the position of use. Fig. 3 is a side elevation of the end of the singletree, showing the position of the parts when the trace is released, and Fig. 4 is an end elevation of a singletree with my improved detacher applied. Similar letters of reference indicate corresponding parts in all the figures.

20 The object of my invention is to provide an attachment for the singletrees of vehicles, for holding and adjusting the traces and for detaching the horse in case of accident.

My invention consists in a clamping-buckle 25 pivoted to the end of a singletree and adapted to engage the trace, and in the combination therewith of a cord extending into the vehicle and arranged for releasing the clamping-buckle. To the end of the singletree A is secured a double eye, B, in which is pivoted the bar C, which is curved outwardly at its center and thickened to form a bearing-surface, a. In the curved bar C, at the middle of its length, and near its inner concave surface, is 30 pivoted a buckle-loop, b, which extends over the bearing-surface a, and is adapted to receive between itself and the bearing-surface the end of the trace D. The surface a is of

about the same width as the trace D. The free end of the curved bar C is apertured to 40 receive the ring c, to which is attached a cord, d. The cord extends toward the middle of the singletree A and passes through an eye, e, projected from the front of the singletree. The cords d from opposite ends of the singletree, after passing through the eyes e, are connected with the single cord g, which extends upward over the dash-board F of the vehicle and within easy reach of the driver. The trace D is fastened in the clamping-buckle by inserting it underneath the loop b, allowing it to draw forward until the loop brings it into firm contact with the bearing-surface a. The firmness of the contact of the trace with the surface a is increased by an increased tension 55 of the trace.

When it is desired to release the traces, the cord g is pulled, turning the curved bar C inward toward the middle of the singletree, thereby turning the buckle-loop b, as shown 60 in Fig. 3, so as to readily release the traces.

Having thus fully described my invention, I claim as new and desire to secure by Letters Patent—

1. The combination of the double eye B, the curved bar C, provided with the bearing-surface a, the loop b, and the cord d, substantially as described.

2. The combination of the double eye B, the curved bar C, provided with the bearing-surface a, the loop b, the cord d, and the eyes e and cord g, substantially as described.

JOHN MARTIN FIEDLER.
